H. HOWARD

SULPHUR BURNER

Filed Dec. 26, 1924

Inventor

Henry Howard

By Byrnes Townsend & Bricklinstein

Attorney

UNITED STATES PATENT OFFICE.

HENRY HOWARD, OF CLEVELAND, OHIO, ASSIGNOR TO THE GRASSELLI CHEMICAL COMPANY, OF CLEVELAND, OHIO, A CORPORATION OF OHIO.

SULPHUR BURNER.

Application filed December 26, 1924. Serial No. 758,221.

To all whom it may concern:

Be it known that I, HENRY HOWARD, a citizen of the United States, residing at Cleveland, in the county of Cuyahoga and State 5 of Ohio, have invented certain new and useful Improvements in Sulphur Burners, of which the following is a specification.

This invention relates to sulphur burners, and more particularly to sulphur burners 10 comprising a rotary part such as the so-called Glens Falls burner, and will be described and illustrated in connection therewith.

The accompanying drawing illustrates one 15 embodiment of my invention.

Referring to the drawing, 1 is a rotary sulphur burner, 2 a combustion chamber into which the gas generated in the burner passes, and 3 is a receptacle for melted sulphur 20 which is delivered to the burner through the pipe 4. The burner 1, combustion chamber 2, and sulphur feeding means 3 and 4 which constitute the essentials of the Glens Falls burner are of known construction and need 25 not be further described. The Glens Falls burner is described on pages 60, 61 and 62 of Bulletin No. 184 entitled "The Manufacture of Sulphuric Acid in the United States" by A. E. Wells and D. E. Fogg, issued by 30 the U. S. Department of the Interior in 1920. 5 is a gas tight housing of any suitable material, such as concrete or steel, which encloses the entire burner, and 6 is a conduit through which air under pressure from a 35 suitable source is delivered into the housing.

In the normal operation of sulphur burners of the Glens Falls type a limited supply of air is admitted at the front end of the burner, that is, at the end opposite the 40 combustion chamber and the resulting gas containing SO_2 and sulphur vapor passes out through the rear end of the burner where it is mixed with air admitted through the adjustable space 7. The resulting gas mixture 45 passes into the combustion chamber 2 in which the combustion of the sulphur is completed and from which the SO_2 -containing gas is delivered to a sulphuric acid plant or other place of use. The burner is operated 50 under reduced pressure that is, under suction or draft produced by a fan, gas pump or the like. In case the gas is to be used in a sulphuric acid contact process, it is generally first purified and dried, then enters a 55 Root's blower, which furnishes the necessary

suction and is delivered by the blower through the contact apparatus, coolers and absorbers. In the case of the sulphite pulp process, a fan or pump is generally placed beyond the absorption system, the whole 60 plant thereby working under reduced pressure.

It is not new to operate sulphur burners under superatmospheric pressure. A burner consisting of a stationary cast iron box or 65 pipe has been used in which the sulphur is burned and to which air is supplied under pressure. Such burners, however, operate in a very uneven manner, and sublimation of the sulphur and great variation in the composition of the gas are very apt to occur. The Glens Falls burner has overcome these difficulties and has very largely displaced other types of burners, both in the sulphuric acid industry and in the sulphite pulp industry. Heretofore, however, it has been necessary to operate the Glens Falls type of burner under reduced pressure, because of the fact that owing to its rotary motion it has been impossible or impracticable to 70 make a satisfactory gas tight joint between the rotary and the stationary parts.

My invention, therefore, consists in placing a housing entirely around the rotating part and adjacent stationary part of the 75 burner, so that no stuffing box or rotary air tight joints are necessary, a standard burner being used and the control of the composition of the gas being maintained in exactly the same manner as when the burner is operated 80 under reduced pressure. From one point of view it is operated under a reduced pressure, as the pressure of the air inside the rotating burner is substantially as much below the pressure in the outside casing as 85 the pressure in the interior of an ordinary burner is below atmospheric pressure.

In operating the burner under pressure in accordance with my invention, air under pressure is supplied to the housing 5 through 100 the pipe 6 from any suitable source. The regulation of the air supply at the front and back ends of the burner is exactly the same as in the normal operation of the burner. The pressure applied to the air supply is 105 transmitted through the gas in the burner and the combustion chamber and may serve to deliver the gas to the place of use at any pressure desired; thus allowing it to be bubbled through an absorbing solution or forced 110

through a purification, contact, and absorption system for the manufacture of sulphuric acid. It will be seen that this eliminates the use of a suction pump operating upon hot or 5 corrosive gases, and at the same time gives a gas of uniform composition, free from sublimed sulphur. Moreover, the volume of gas to be handled is materially reduced, as 10 only cool air is handled by the blower or compressor.

It is of course evident that the principles 15 of my invention are applicable to sulphur burners other than rotary burners of the Glens Falls type, for instance, to burners 20 which do not comprise a moving or rotating part, but the invention is particularly designed to combine the advantages of the Glens Falls type of burner,—principally the production of a gas of uniform SO_2 content, 25 with the advantages incident to operating sulphur burners under pressure,—the elimination of pumps operating upon hot corrosive gases, and to overcome the mechanical difficulties heretofore encountered in attempting to operate rotary burners under superatmospheric pressures.

Instead of supplying the sulphur to the 30 burner in liquid form as described above, it may be supplied in solid form by means of a standard screw conveyor or in any other suitable manner.

I claim:

1. A sulphur burner comprising a receptacle for sulphur to be burned, having an air inlet opening and a gas discharge opening, a chamber enclosing said receptacle having an air inlet opening and a gas discharge opening, and means for delivering air under superatmospheric pressure into said chamber through its air inlet opening. 40

2. A sulphur burner comprising a rotary receptacle, means for supplying sulphur to said receptacle, a combustion chamber communicating with said receptacle, means for admitting air into said receptacle and into the gas stream passing from said receptacle to said chamber, a gas tight housing surrounding said means for admitting air, and means for supplying air to said housing under superatmospheric pressure. 45

3. A sulphur burner comprising a rotary receptacle, a stationary chamber, a conduit for the passage of gas from said receptacle to said chamber, means for admitting air into said receptacle, means for admitting air into said conduit, and a gas tight housing surrounding said receptacle and at least a portion of said conduit enclosing said means for admitting air. 55

In testimony whereof, I affix my signature.

HENRY HOWARD.
